PRINTING DEVICE

Franklin E. Curtis, East Cleveland, Ohio, assignee, by mesne assignments, to Addressograph - Multigraph Corporation, Cleveland, Ohio, a corporation of Delaware

Application April 12, 1935, Serial No. 16,065

22 Claims. (Cl. 101—57)

This invention relates to a printing device for printing sales slips and the like, involving the use of a customer's token carrying his address. The device is utilizable in that system of customers' credits now frequently employed in large retail stores, where a metallic token, in the form of an embossed address plate, is issued to customers entitled to a certain amount of credit. The same token may apply to several different stores, each store having an individual indication on the token not applicable to any of the other stores. When the customer presents his token to the proper store, the salesman utilizes it in printing one or more sales slips, and if desired an entry in the salesman's sales book, with the result that credit is given only to those entitled to it, the address on the account slip and delivery slip is necessarily correct, and there is a material saving in time in making out such slips.

Sales slip printing devices operating according to the above outlined system are in use. It is the object of this invention to materially simplify and cheapen the construction and operation of the printing device, as well as to provide a more efficient token. To that end I have provided a very simple printing device which is normally locked against operation, and a very simple form of token which, when presented in proper position to the proper printing machine, automatically releases such lock, enabling the imprint to be made. On the other hand, the machine is inoperable when a token not intended for that store is presented. This has the advantage of not only protecting the store but of visually indicating to the customer the reason why the credit will not be extended to him.

The above characteristic of operation and various features of construction included within my invention, will become apparent from the following detailed description of a preferred embodiment illustrated in the drawings.

In the drawings, Fig. 1 is a plan partly broken away of my printing machine showing the slide which carries the token in the extended position 45 it has when the token is being placed therein; Fig. 2 is a longitudinal vertical section through the machine with parts in the position of Fig. 1, the plane of this view being indicated by the line 2—2 on Fig. 1; Figs. 3 and 4 are vertical sections 50 through the machine in the same plane as Fig. 2, showing the slide in the innermost position—Fig. 3 showing the operation with a token intended for that machine and the platen depressed to make the impression, while Fig. 4 55 shows the condition when the token is not of

the character proper for that machine; Fig. 5 is a vertical section through the bed of the machine and a portion of the platen at right angles to Figs. 2, 3 and 4, as indicated by the line 5—5 on Fig. 3. The remaining figures indicate the token—Fig. 6 showing it as suitable for one store only; Fig. 7 as suitable for another store only; Fig. 8 as suitable for both stores; Fig. 9 is a fragmentary view of a token suitable for a considerable number of stores; Fig. 10 is a perspective of 10 a portion of the token looking at the underside thereof adjacent one end.

As shown in Figs. 1 to 5 inclusive, the frame of my machine comprises a hollow casting 10 of inverted box-like form having substantially vertical side walls 11 terminating below in lateral supporting flanges 12, front and back walls 13 and 14, and a top plate 15 joined at the top to the various walls. The top web forms really the bed of the machine and receives indirectly the 20 printing blow as hereinafter explained.

Extending from the box-like portion of the frame, preferably in line with the side walls 11, are vertical webs 16, which carry near their upper edges a horizontal rod 20 on which is mounted the platen arm 30. This arm carries on its underside a rubber bed or similar platen member 31. The top of the arm is formed into a rounded smooth knob-like portion 32, adapted to be readily engaged by the operator's hand in 30 depressing the arm. The arm is normally held elevated, in the position shown in Figs. 2 and 4, by a coiled torsion spring 21 (Fig. 1) which surrounds the rod 20 and has one free end bearing against the underside of the platen arm and the 35 other end against a pin 17 carried by one of the frame extensions 16.

A slideway is formed in the top of the bed 15 directly beneath the platen and extending in the general length thereof. The slideway, as shown, 40 comprises a shallow groove 18 in the bed and a pair of strips 40 secured to the bed and overhanging the groove. Mounted in the slideway is a flat horizontal bar 50 adapted to reciprocate readily. This bar has in its upper face a shallow 45 depression 51 in which a token A may be seated. When the slide 50 is extended, as shown in Figs. 1 and 2, the recess 51 is entirely beyond the frame and thus exposed to allow the token to be placed therein. When the slide is in its innermost position, as shown in Figs. 3 and 4, the token receiving recess is directly beneath the platen.

The outer end of the slide 50 may be formed into a flat knob-like portion 52 to enable it to be more readily grasped by the operator's fingers. 55

Near its inner end the slide is shown as carrying a downwardly extending pin 54, which occupies a narrow groove 19 formed in the bed deeper than the base of the wide groove 18. This pin, 5 by impinging the end of the groove 19, as shown in Figs. 1 and 2, limits the outward movement of the slide.

To hold the slide temporarily in its innermost, or printing position, and at the same time allow 10 it to be readily drawn out manually, I provide a spring detent bearing against it. This detent is shown as comprising a vertical pin 60, mounted in the bed and pressed upwardly by a leaf spring 61 secured to the underside of the bed. The upper 15 end of the pin 60 is rounded and is adapted to coat with an indentation 57 formed in appropriate position on the underface of the slide 50.

The latch mechanism, which normally locks 20 the platen and is released by the individual indication on the token, is shown in locked position in Figs. 2 and 4, and in released position in Fig. 3. This mechanism includes a dog 70, pivotally attached at 71 to one of the frame webs 16. The 25 upper end of this dog may stand directly below a shoulder 35 formed on the platen arm adjacent the pivot 20. As shown, the dog is cut away in a curve at 72 adjacent its upper end to allow the end to come close to the rounded end portion of 30 the platen arm. The dog 70 is connected by a link 73 with a rock arm 74 on a rock shaft 75, journaled in the frame webs 16. Extending upwardly from this rock shaft is another rock arm 76 which carries a blade 77 occupying a short 35 groove 78 in the base of the slideway 18.

The latch is normally retained in the position shown in Fig. 2 by suitable springs. Thus I have shown a coil spring 80, which may be attached at 40 one end to the pivot pin connecting the link 73 to the arm 74 and at the other end to the stud 71 carrying the dog 70. I have shown also a spring 81 mounted on the rock arm 76 and bearing against the end of the pivoted blade 77. The spring 83 drawing rearward on the rock arm 74 45 tends to maintain the dog 70 in the locking position shown in Fig. 2, and the blade 77 in its forward position, the front end of this blade being kept down in its groove in the bed by the spring 76.

50 The slide 50 is formed on its underside at the inner end with a downwardly facing groove 58 positioned in alignment with the latch blade 77. Extending crosswise of the slide at the outer end 55 of the groove 58 is a vertical opening 59 leading downwardly through the slide from the plate receiving recess 51.

It results from the construction described that when the slide is shoved inwardly the groove 58 60 will pass over the latch blade 77. The length of that groove plus the width of the opening 59 is such that the slide may reach its extreme innermost position (as determined by a pin 90 in the slide engaging the face of the base) without engaging the blade 77. This is illustrated in Fig. 4. 65 However, if the token resting in the recess 51 has a downward projection occupying the opening 59 in a position to engage the end of the blade 77, such engagement will effect the release of the latch when the slide comes into its innermost position as shown in Fig. 3, and thereupon 70 the platen may be manually depressed to effect the printing. Thus, the machine is normally locked and is only released when a token having 75 a downward projection in position to engage the

control blade is placed in the slide receiving recess.

The tokens, illustrated at A in the drawings, are thin metal plates adapted to be readily embossed with upwardly facing printing characters as indicated at a. Each token is provided with at least one downward projection a¹. This projection may be made on the token in any suitable manner. I find it most satisfactory to make it by forming a short transverse cut in the token and pressing downwardly the metal just back of the cut to provide an abrupt downwardly extending edge a², as illustrated in Fig. 10.

Fig. 6 illustrates the projection a¹ formed in position to coat with the control blade 77 in the particular machine shown in the drawings. If the projection a¹ were formed in the position indicated at a³ in Fig. 7, it would not engage with the particular machine shown, but might engage with a similar machine which had the control blade 77 in a position to occupy a groove in the slideway 18 located as indicated by the broken lines 95 in Fig. 1, the slide in that case having on its underside a registering groove 96.

The token A of Fig. 8 has two projections a¹ and a³ and is adapted to coat either with the specific machine shown in full lines in the drawings, or with a similar machine employing the grooves 95 and 96 and the correspondingly positioned control blade 77.

It will be seen that my token is adapted to be formed with a number of projections adjacent its end to represent various stores, and the machines in any store are readily made special to that store by cutting the grooves 78 and 58 or 95 and 96 in the special location which corresponds to the location of the token projection appertaining to that store.

If there is not sufficient room across the end of the token for projections for all of the stores desired, a second parallel row of projections may be formed back of the first row, with the projections of the second row directly behind the spaces between projections of the first row. Such first and second rows are indicated at a⁴ and a⁵ on the token illustrated in Fig. 9. In this case the control blade, being thinner than the spaces between the projections of the first row, may be positioned so as not to be engaged by them, and still engage the projections of the second row. The movement contributed to the control blade by the engagement of the projections of the second row is sufficient to free the latch dog 70 from engagement with the platen arm and the engagement of the first row of projections will 55 simply move the latch dog further idly.

Any suitable means may be employed to provide pigment matter for making the impression. It is desirable, however, that no inking surface engage the token itself so that the latter may be 60 clean when handed back to the customer without the necessity of wiping. To that end, one may employ carbon sheets associated with the sales slips, or an inking ribbon backed by an impervious protecting strip of paper or similar material might 65 be used. I find it very satisfactory, however, to employ for this purpose a rolled-up strip of carbon paper, carboned on one side only, and that is the construction shown in the drawings. There a carbon paper strip, designated 100, is employed, 70 having the carbon coating facing upwardly where the paper crosses the slideway. In Figs. 3, 4 and 5, B indicates a sales slip or similar page adapted to overlie the inking medium 100 and be imprinted by the platen.

As shown, the carbon coated strip 100 extends over the slideway and thence downwardly through openings 101 in the frame and is then mounted on a pair of spools 102. As shown, the 5 inner end of the paper passes in through a diametric slot 103 of the spool to anchor the paper. These spools are journaled at one end on pins 105 carried by the base wall 14 while at the front end they are connected to pins 106 which carry 10 knurled knobs 107 at their outer ends. By rotating one knob 107 or the other, the inking strip may be fed in either direction as desired, to present a fresh face for the imprint. The pins 106 may be pulled out of the spools by their knobs 15 to enable the removal of the spool for the mounting of a fresh inking web, and thereafter the spool with the web wound on it is placed in alignment with the pin, and by merely shoving in of the pin, it becomes locked to the spool, the 20 spool and pin having angular portions which engage in this position so that the knob may turn the spool.

It will be seen from the description given that my machine is extremely simple in construction, 25 comprising primarily a base carrying a slide, a platen arm and a lock controllable directly by the token on the slide. The inking medium may be conveniently carried in the base of the machine as shown, or might be dispensed with and the 30 inking pigment supplied by carbon sheets interleaved with sales slips.

In using the machine, the operator merely places the token in the recess in the slide, moves the slide inwardly, and then lays above the inking 35 medium the sales slip or plurality of them with carbon between them, as indicated generally by the character B in the drawings, delivers a manual blow to the knob on the platen arm, and then draws out the slide and hands the token back to 40 the customer.

The feature of the token projections occupying the slide opening as shown not only provides for control of the latch as desired, but is effective to prevent the proper token being improperly inserted. That is to say, if the token is placed in the 45 recess upside down or wrong end to, its engagement with the ledges 40 will prevent the slide being moved into position, and thereupon the operator immediately places the token in the 50 proper position in the slide recess. The entire operation of placing the token, moving the slide inwardly, making the impression, and handing the token back to the customer, requires a very short time.

55 I claim:

1. The combination of a base adapted to support a printing plate, a manually operable platen arm pivotally mounted on the base, a platen on the arm adapted to coact with a plate on the support when the arm is lowered, a continuously active lock for the platen arm, and means controlled by the plate to release the lock.

2. The combination of a support for an address plate and a manually operable platen to coact with a plate on the support, a lock normally preventing movement of the platen, said lock being continuously active and having releasing means adapted to be engaged by a specially positioned shoulder on the plate.

70 3. In a device of the character described, the combination of a base, a reciprocable slide movably carried thereby and formed to receive a customer's token, a platen adapted to coact with the token on the slide, and means for preventing

effective printing when an improper token is properly placed on the slide.

4. In a device of the character described, the combination of a base having a slideway on its upper face, a manually operable slide mounted in the slideway and having a recess in its upper face, said recess being adapted to be beyond the base or over the base according to the position of the slide, a platen arm pivotally carried by the base, and a planular platen on the arm adapted to coact with a customer's token on the positioned slide when the arm is lowered.

5. In a device of the character described, the combination of a base, a manually operable movable platen, a lock for the platen, and a manually operable slide on the base adapted to carry a customer's token into position for printing coaction with the platen, said token having means for releasing the lock.

6. The combination of a base having a slideway, 20 a reciprocable slide therein adapted to carry a customer's token, a manually operable platen arm hinged to the base, a normally active lock preventing movement of the platen arm, and means whereby a properly positioned shoulder 25 on the token may release the lock.

7. In a device of the character described the combination of a base, a platen arm hinged thereto, a slide mounted on the base having an upwardly opening recess adapted to receive a customer's token, which may be carried by movement of the slide into printing position, a lock for the platen arm, mechanism movable in the same direction as the positioning movement of the slide to release the lock, said mechanism 35 being positioned to be engaged by a properly positioned shoulder on the token on the slide.

8. In a device of the character described the combination of a base having a slideway on its upper surface, a slide mounted in the slideway 40 and adapted to carry a customer's token, said slide having an opening through it which may be occupied by a downward projection on the token, a printing arm pivoted to the base, a latch for the printing arm having a releasing member 45 positioned to be engaged by an aligned projection on the token.

9. The combination of a base having a slideway, a slide in the slideway, a recess in the upper surface of the slide adapted to receive a customer's token, an opening through the slide registering with the recess, whereby the opening may receive a projection on the underside of the token, a platen arm pivoted to the base, a locking dog for the platen arm, a movable member 50 adapted to operate the dog and positioned to be engaged by an aligned downward projection in the slide opening of a token in the recess.

10. The combination of a base, a slide mounted thereon, a recess in the upper face of the slide 60 adapted to receive a customer's token, a platen arm pivotally carried by the base, and a planular platen on the arm adapted to coact with the customer's token by the lowering of the arm when the slide has positioned the token over the base, 65 an abutment normally standing in the path of a shoulder on the arm and preventing printing thereby, and mechanism actuated by a shoulder in a certain position on the token to move the dog to idle position.

11. The combination of a base, a platen arm pivoted thereto and carrying a platen adapted to coact with a token supported by the base, a dog normally standing in the path of a shoulder on the platen arm and preventing printing ac- 75

- tion of the platen arm, a blade movably carried by the base in position to be engaged by a projection on a customer's token, and a rock shaft carried by the base having a pair of rock arms 5 thereon, one connected with the blade and the other with the dog.
12. A printing device having a base with a slideway therein, a slide in the slideway adapted to receive a customer's token and carry it into 10 position for coaction with the platen, and a platen pivoted to the base and adapted to coact with the positioned token, and means on the printing device adapted to be controlled by a definitely positioned shoulder on a token to prevent the 15 printing operation in the absence of a shoulder in the proper position on a token which is on the slide.
13. The combination with a normally inoperative printing machine adapted to print from a 20 customer's token having a particular index, and means under the control of said index while the token is in printing position in the machine to render the machine operative to print.
14. The combination of a manually operable 25 printing device having a continuously active lock normally preventing operation and a customer's token providing a printing form and an index adapted to release the lock.
15. The combination of a manually operable 30 printing device, having a continuously active lock normally preventing operation and a customer's token having embossed printing characters adapted to coact with the device to make an imprint, said token having a fixed shoulder 35 adapted to differ on different tokens to release the lock only on presentation of a token having the proper shoulder.
16. In a machine having a platen adapted to coact with and print from individually presented 40 customer tokens manually placed in the machine, means to prevent such coaction, said means being rendered inoperative by proper placement in printing position of a token suitable for printing in the machine, whereby to enable coaction of the platen and token.
17. In a printing machine for individual customer tokens, the combination of printing means, and locking means normally preventing a printing 45 operation, which locking means is continuously active and is released by the arrival in printing position of a manually inserted token suitable for printing in that machine whereby to enable a printing operation thereon to be effected.
18. In a device of the character described, the combination, with a support and platen, of a customer's token comprising a planular address plate having embossed characters and a projection on one face of the plate extending out of 5 the plane thereof, a latch and operating mechanism therefor adapted to coact with a correspondingly positioned projection on the address plate whereby said address plate may coact with the platen or not, according to the position of 10 said projection on the plate.
19. The combination with a printing device, of a customer's token adapted to provide the printing form and comprising an address plate having embossed characters and fixed projections from 15 one face of the plate to present a plurality of abrupt shoulders in a transverse row across the end portion of the token beyond the region of the address, a normally active lock for the printing device, and release mechanism for the lock 20 adapted to be engaged and controlled by one of said shoulders.
20. In a machine having a manually operable platen and a holder adapted to receive customer tokens in printing relation to the platen, mechanism normally active to prevent coaction of the 25 platen and a token in the holder, means to release the preventing mechanism, said holder being formed to receive tokens of a given class irrespective of the species thereof, said releasing 30 means cooperating with one species and not with another of the same class.
21. A machine in which customer tokens are inserted individually by hand and printed from by relative movement of a platen and token toward each other effected manually, characterized in that the machine is normally continuously locked against operation, and releasing mechanism for the lock operable by a token suitable 35 for printing in the machine when properly placed 40 in printing position therein.
22. In a printing machine arranged to receive and print from tokens which are individually and manually placed in the machine, a platen and a support for the tokens, one being movable 45 relative to the other to print, and means to prevent said relative movement of the platen and support toward each other, said means being releasable by proper tokens, properly positioned, but not by improper tokens however positioned, 50 or by proper tokens improperly positioned.

FRANKLIN E. CURTIS.
